UNITED STATES PATENT OFFICE

HIRAM C. CALLENDER, OF INDIANAPOLIS, INDIANA, ASSIGNOR TO RIBBON MITER MACHINE COMPANY, OF INDIANAPOLIS, INDIANA, A CORPORATION OF INDIANA

DESIGN FOR BUILDING GLASS OR THE LIKE

Application filed September 12, 1929. Serial No. 32,730. Term of patent 14 years.

To all whom it may concern:

Be it known that HIRAM C. CALLENDER, a citizen of the United States, residing at Indianapolis, in the county of Marion and State of Indiana, have invented a new, original, and ornamental Design for Building Glass or the like of which the following is a specification.

Referring to the accompanying drawing, forming a part thereof, Figure 1 is a plan view of a window glass showing my new design and Fig. 2 is a section through the glass on the line 2—2 in Fig. 1.

The body of the glass sheet, being those portions between the unstippled stripes, is translucent, while the stripes themselves are transparent. The stippling shown in the drawing is continued throughout.

I claim:

The ornamental design for building glass or the like, substantially as shown and described.

In testimony whereof I affix my signature.
HIRAM C. CALLENDER.
